UNITED STATES PATENT OFFICE.

ALBERT W. TILLINGHAST, OF PHILADELPHIA, PENNSYLVANIA.

SHOE-SOLE ATTACHMENT.

No. 844,057.

Specification of Letters Patent.

Patented Feb. 12, 1907.

Application filed February 12, 1906. Serial No. 300,678.

To all whom it may concern:

Be it known that I, ALBERT W. TILLINGHAST, a citizen of the United States, residing in Philadelphia, Pennsylvania, have invented 5 certain Improvements in Shoe-Sole Attachments, of which the following is a specification.

My invention relates to shoe-soles, and consists of certain improvements in suction-pads or antislipping structures designed for attachment to the shoe-sole or to be combined therewith and adapted more particularly for use by golf-players, although it is equally adapted for use with all forms of 15 sporting-shoes.

My invention is fully shown in the accompanying drawings, in which—

Figure 1 is a cross-sectional view of the shoe-sole attachment made in accordance 20 with my invention before the same is applied to the shoe. Fig. 2 is a similar sectional view showing the attachment as applied to the shoe-sole. Fig. 3 is an inverted plan view of a shoe-sole, showing the attachment 25 in place. Fig. 4 is a cross-sectional view illustrating a modification of my invention. Figs. 5 and 6 are views of modified forms of retaining or securing means. Fig. 7 is an enlarged view of a portion of Fig. 1. Fig. 8 30 is a view of a shoe-sole with which the suction-pad or antislipping device is integrally combined, and Fig. 9 is a view illustrating a detail of my invention.

As illustrated in the accompanying drawings, my invention relates to the disk structure shown in Fig. 1 and consists of certain improvements in this article, which in general terms comprises a rubber or rubber-containing body 1, having an annular wall or 35 rim 2, and an integral web 3, reduced in thickness and joining said wall, the whole adapted to fit against the shoe-sole and be secured thereto by suitable means.

My improvements are directed to several 45 novel features in connection with this device and are as follows: By beveling the outer contour of the annular wall 2 toward the sole, as shown at 4, and providing a comparatively thin edge 5 for this portion of the 50 attachment, which projects below the under surface of the same, as clearly shown in Fig. 1, the rubber or other material of which the article is made will be spread by the securing means when the device is applied to the sole, 55 and will insure closer contact with such sole, as clearly illustrated in Fig. 2. The under

surface of the member 1 is slightly dished and is provided with a section of canvas webbing 6 in my improved device, which canvas is stopped a short distance from the edge of the disk, as shown in the several figures of the drawings, notably in Fig. 7, so that when the latter is compressed in the manner shown in Fig. 2 there will be no obstruction to prevent the edge of the rubber or other material 65 making close contact with the sole. This close contact, coupled with the beveled edge of the disk, which assumes the curved form shown at 7 in Figs. 2 and 4, enables the attachment to be firmly secured and used without danger of separation from the sole and avoids the consequent picking up of small stones, dirt, &c.

The central web 3 of the article is formed integral with the annular projecting portion 75 2, and in my improved form of the structure I recess said web centrally, as shown at 10, so that the hollowing out of the ordinary shoe-sole effected by the foot in walking will never be sufficient to cause the under surface of 80 such web to contact with the ground. In my improved structure the inner wall of the projection 2 is undercut at 11, so as to increase the suction of the device. This attachment may be secured to the shoe-sole by 85 screws 12 passing through apertures in the projecting wall 2, as illustrated in Figs. 2, 3, and 4 of the drawings, and these screws are applied in the manner shown in Fig. 3, the greatest number being disposed at the front 90 of the attachment. In Figs. 5 and 6, however, I have shown modified forms of attaching means, that in Fig. 5 comprising an annular ring 15, fitting the inner undercut portion of the wall 2, which serves also as a stiffening member for said wall, while in Fig. 6 an annular plate 16 is let into the under surface 95 of the device. In both instances the screws 12 pass through these metal portions. When fastening means of the character shown in 100 Figs. 5 and 6 are employed, a better contact of the projection will be secured, as its surface is continuous.

In Fig. 8 I have shown a rubber sole with which the antislipping device or suction-pad 105 is integrally combined, such structure embodying the improvements forming the subject of my invention, which are also shown in the other views and specifically referred to. This sole will be sewed to the welt or other 110 sole of the shoe in the usual manner and may also have its surface covered with any cement

preparatory to being sewed down. Instead of having the flanged portion 5 extend entirely around the sole, as illustrated in Fig. 3, I may arrange it at the forward and rear portions only and slightly greater in length, as clearly illustrated at 17 in Fig. 9.

I claim—

1. A shoe-sole attachment of the type comprising an annular plate having a raised circumference forming a projecting rim being designed for contact with the ground and connected by an integral web, said projecting rim having its inner wall undercut.
2. A shoe-sole attachment of the type comprising an annular projecting wall or rim connected by an integral web, characterized by having said web strengthened by a body of canvas applied to the under side, which canvas is stopped short of the edge of the attachment, and a flange projecting beyond said canvas to be flattened against the shoe-sole.
3. A shoe-sole attachment of the type comprising an annular projecting wall or rim connected by an integral web, characterized by having an undercut inner wall for said annular projecting portion, an annular ring fitting said wall, and fastening means passing

through said ring to secure said attachment to the sole of a shoe.

4. A shoe-sole attachment of the type comprising an annular projecting wall or rim connected by an integral web, characterized by having its body recessed or undercut, a metallic member fitting said undercut or recessed portions, and fastening means passing through said metallic member.

5. A shoe-sole attachment of the type comprising an annular projecting wall or rim connected by an integral web, characterized by having an undercut inner portion for said annular projecting rim or wall, a metallic member fitting said undercut portion and serving as a stiffening means for said rim or wall, and fastening means passing through the metallic member and serving to hold the structure to the sole of the shoe.

In testimony whereof I have signed my name to this specification in the presence of two subscribing witnesses.

ALBERT W. TILLINGHAST.
